UNITED STATES PATENT OFFICE

SAMUEL MCMULLAN, OF DOWNSERS GROVE, AND ARTHUR ERHOLD SCHULZ, OF CHICAGO, ILLINOIS, ASSIGNEES TO WESTERN ELECTRIC COMPANY, INCORPORATED, OF NEW YORK, N. Y., A CORPORATION OF NEW YORK

WIREDRAWING APPARATUS

Application filed March 26, 1926. Serial No. 97,644.

This invention relates to wire drawing apparatus, and more particularly to improvements in operating control mechanisms therefor.

The invention is particularly applicable to that class of wire drawing apparatus embodying a capstan for drawing the wire through one or more reducing dies, and a coiling drum for taking up the drawn wire. In the operation of apparatus of this type, the wire may sometimes break due to one cause or another, and unless the coiling drum is immediately stopped, such breakage may in some instances be followed by a sudden uncoiling of the drawn wire and a sweeping stroke of the broken end, constituting a source of danger which must be guarded against. Furthermore, the expansive uncoiling of the wire which results from a continued rotation of the coiling drum after such breakage incurs much labor and loss of time by the attendant and also decreases the efficiency of the apparatus.

The principal object of the present invention is the provision, in a wire drawing apparatus, of a simple and efficient mechanism for positively stopping the coiling drum when the wire breaks or comes to an end.

Other objects and advantages of the invention will become apparent from the following detailed description, reference being had to the accompanying drawings, wherein

Fig. 1 is a front elevation of a wire drawing apparatus embodying the features of the invention;

Fig. 2 is a fragmentary plan view thereof;

Fig. 3 is an enlarged elevational view, partly in section, of the improved control mechanism;

Fig. 4 is a plan view of the mechanism shown in Fig. 3, and

Fig. 5 is a skeleton sectional view taken on the line 5—5 of Fig. 2 showing a portion of the driving mechanism and clutch.

Although the invention is herein illustrated and described in connection with a specific type of wire drawing apparatus, it is to be understood that the invention is capable of other applications and should be

limited only by the scope of the appended claims.

Referring now to the drawings in detail and particularly to Figs. 1 and 2 thereof, the numeral 10 indicates a bed or base plate on which is mounted a housing 11 provided with an upper suitably hinged section or cover 12. Supported upon the base plate 10 to the rear of the housing 11 is a second housing 14, within which the driving mechanism of the apparatus is mounted. Suitably journaled within the housing 14 is a pair of horizontally disposed shafts 17 and 18, the shaft 17 being driven by means of a suitable sprocket chain drive indicated at 19 (Fig. 2) from a motor (not shown) positioned in a basement or pit located below the apparatus. The shaft 18 is driven at a suitable speed from the shaft 17 by means of a suitable sprocket chain drive indicated at 20. The shaft 17 extends through the rear wall of the housing 11 and has secured at its forward end a conical or stepped drawing capstan 21 which is provided with a plurality of steps of gradually increasing diameters. The shaft 18 also extends through the rear wall of the housing 11 and rotatably carries, at its forward end, a plurality of independent sheaves 22 of gradually increasing diameters. Secured to the shaft 18 adjacent to the smallest sheave 22 is a grooved pulley 23.

Secured on the inner side of the rear wall of the housing 11 intermediate the shafts 17 and 18 is a die box or support 24 adapted to hold a plurality of wire drawing dies 25, the dies being positioned and retained therein with their axes suitably disposed with respect to the periphery of the stepped capstan 21, the grooved pulley 23, and the sheaves 22. Suitable means (not shown) is provided for lubricating the dies 25 while mounted in the die box 24 and also for lubricating the capstan 21.

After the dies have been accurately strung upon the wire or rod which is to be drawn, it is passed over a guide sheave 27 rotatably mounted at the left end of the apparatus (Fig. 1) and then over the top of and around the grooved pulley 23. After the wire has

been wrapped one or more turns around the pulley 23, the first of the series of dies 25 is properly positioned in the die box 24 and the wire is then passed around the smallest 5 capstan 21 and then around the smallest sheave 22. The second of the series of dies 25 is then properly positioned in the die box 24 and the wire is then passed over and around the second smallest capstan 21 and the 10 second smallest sheave 22. This procedure is continued until the last die 25 has been properly positioned in the die box and the final reducing die 26 has been properly positioned as shown in Fig. 2. The end of the 15 wire is then passed through an apertured member 30 which constitutes a part of the improved control mechanism hereinafter described.

The end of the wire is then suitably attached to a rotatable drum 33 of a coil take-up mechanism indicated, generally, by the numeral 32. The drum 33 is rigidly fixed to the upper end of a vertically disposed shaft 34 suitably journaled in a supporting standard 35 secured to the base 10. The shaft 34 is driven from a horizontally disposed shaft 37 (Figs. 2 and 5) by means of suitable gearing (not shown).

Suitably journaled within the housing 14 20 is a horizontally disposed shaft 39 which is driven from the shaft 17 by means of a suitable sprocket chain drive 40. The shaft 39 is operatively connected to a suitably journaled vertically disposed shaft 42 by means 25 of bevel gears 43 and 44. Keyed to the lower end of the shaft 42 is a bevel gear 45 meshing with a bevel gear 46 secured to the shaft 37.

In Fig. 5, the reference numeral 48 indicates a suitable friction clutch which is adapted to operatively connect the sprocket chain drive 40 with the shaft 39, thereby controlling the rotation of the shaft 39 from which the coiling drum 33 is driven. The clutch 45 is manually controlled by a lever 50 secured to one end of a rod 51 suitably journaled in the frame of the apparatus. Keyed to the rod 51 is a cam 52 which operatively engages a roller 53 carried at the lower end of a shifting fork 54, the shifting fork being pivoted intermediate its ends as indicated at 55.

For a more detailed disclosure of the wire drawing apparatus thus far described, reference is directed to the copending application 55 of William F. Hosford and David Levinger, Serial No. 756,405, filed December 17, 1924. Since the present invention is not concerned with the details of any particular construction or type of wire drawing apparatus, those 60 details have been omitted from this application for the sake of simplicity.

Referring now particularly to Figs. 3 and 4, the improved automatic control mechanism comprises a vertically disposed spring 65 actuated bar 56 which carries at its upper end

the apertured member 30 hereinbefore referred to. The bar 56 is loosely mounted in a vertically disposed cylindrical tube 57 which is rigidly secured to the base 10. Fas- 70 tened to the upper end of the tube 57 is a cap 58 which is suitably apertured to pro- vide a sliding fit for the bar 56. Encircling the bar 56 and disposed between the cap 58 and a nut 60 threaded at the lower end of the bar is a compression spring 62 which tends 75 to urge the bar downwardly.

Secured to the rod 51 adjacent to the hand lever 50 is a pinion 64 having meshing therewith a vertically disposed rack 65 slidably mounted in a cylindrical hollow member 66 80 secured to the base 10. Fastened to the upper end of the member 66 is a cap 67 which is suitably apertured to provide a sliding fit for the rack 65. Encircling the rack 65 and disposed between the cap 67 and a disk 68 fastened to the lower end of the rack is a compression spring 70 which tends to urge the rack downwardly. Referring to Fig. 3, it is obvious that a downward movement of the rack 65 causes the pinion 64 to rotate in a clockwise direction, which motion is transmitted through the rod 51 to the cam 52, thereby disengaging the clutch 48 causing the apparatus to come to a stop.

During the normal operation of the apparatus, the rack 65 is held in its uppermost position by means of a latch 71 engaging a slot 72 formed in the back of the rack 65 (Fig. 3). The latch 71 is secured to a pin 73 rotatably journaled in parallel ears 74, 74 100 formed integral with the cap 67. Fastened to an outwardly projecting end of the pin 73 is a lever 75, the free end of which is movable in a vertical slot 76 formed in the tube 57.

After the wire with the dies properly 105 strung thereon has been threaded through the apparatus and the end thereof has been inserted through the apertured member 30 and fastened to the coiling drum 33 as hereinbefore described, the rotation of the coiling drum is started by turning the clutch handle 50 in a counter-clockwise direction to engage the clutch, whereupon the latch 71 engages the slot 72 in the rack 65, thereby holding the clutch in its engaged or operative position against the tension of the spring 70. A compression spring 78 mounted in the lower portion of the tube 57 serves to urge the free end of the lever 75 upwardly thereby causing engagement of the latch 71 with the 110 slot 72.

The tension in the wire passing through the member 30 to the coiling drum normally predominates over the tension of the spring 62 to hold the bar 56 in its raised position 115 (Fig. 3), wherein the lower end thereof does not engage the lever 75. When a break occurs in the wire or when the end of the wire has passed through the apparatus, it is obvious that the amount of force or tension of 120

the wire urging the bar 56 upwardly drops to zero almost instantaneously. The energy stored in the spring 62 overcomes the tension of the spring 78 and suddenly pushes the bar 56 downwardly whereby the lower end thereof strikes the lever 75 turning it in a clockwise direction. This causes the latch 71 to become disengaged from the slot 72, whereupon the energy stored in the spring 70 serves to push the rack 65 downwardly, thereby rotating the pinion 64 together with the rod 51 in a clockwise direction. This motion actuates through the cam 52 and the shifting fork 54 to disengage the clutch, thereby stopping the rotation of the coiling drum.

Fastened to the lower end of the rack 65 is a leather washer 80 fitting snugly inside the cylinder 66. This provides an air cushion or dash pot for the rack 65 which is controlled by means of a valve 81 serving to regulate the speed at which the clutch handle is thrown. A compression spring 84 serves to further cushion the downward stroke of the rack 65.

A foot treadle 85 and a link 86 connected directly with the arm 75 enables the operator to stop the coiling drum at any time, should it become necessary to do so before the entire coil has been applied thereon.

The above described clutch actuating mechanism is a valuable improvement in wire drawing apparatus since it eliminates the necessity of close supervision by the operator, thereby permitting him to efficiently attend to more than one machine. With the use of a clutch control mechanism embodying the features of this invention the operator is not required to hurry to the clutch handle in order to stop the coiling drum when the wire breaks or comes to an end. Furthermore, much time is saved since the clutch is disengaged automatically and immediately upon the breaking of the wire or upon the end thereof passing through the apparatus, thus enabling the operator to unload the coil and again start the operation of the apparatus in much shorter time.

What is claimed is:

1. In a wire drawing apparatus, a wire coiling element, means for driving said element, a clutch for controlling said driving means, a pinion for operating said clutch, a spring actuated rack for operating said pinion, and a resiliently mounted latch actuated by the wire being coiled for controlling the actuation of said rack.

2. In a wire drawing apparatus, a coiling element for taking up drawn wire, means for driving said coiling element, a clutch for controlling said driving means, a rotatable shaft for operating said clutch, a pinion secured to said shaft, a spring actuated rack engaging said pinion, a resiliently mounted latch controlling the actuation of said rack,

and a spring actuated plunger controlled by the wire being coiled for operating said latch.

3. In a wire drawing apparatus, a wire coiling element, means including a clutch mechanism for driving the element, a pivoted member for operating the clutch mechanism, a rotatable shaft carrying a cam for operating the pivoted member, a pinion secured to the shaft, a spring actuated rack engaging the pinion, a resiliently mounted latch for controlling the actuation of the rack, and a spring actuated plunger controlled by the wire being coiled for operating the latch.

4. In a wire drawing apparatus, a wire coiling element, means including a clutch mechanism for driving the element, a pivoted member for operating the clutch mechanism, a rotatable shaft carrying a cam for operating the pivoted member, a pinion secured to the shaft, a spring actuated rack operatively engaging the pinion, and means actuated by the wire being coiled in response to variations in the tension thereof for controlling the operation of the rack.

In witness whereof, we hereunto subscribe our names this 11th day of March, A. D. 1926.

SAMUEL McMULLAN.
